METHOD AND APPARATUS FOR STARTING
AND OPERATING GASEOUS ELECTRIC
DISCHARGE DEVICESLeroy J. Buttolph, Grantwood, N. J., assignor to
General Electric Vapor Lamp Company, Hoboken, N. J., a corporation of New Jersey

Application July 26, 1932, Serial No. 624,838

10 Claims. (Cl. 176—45)

The present invention relates to electric gaseous discharge devices generally, and in particular to vapor arc devices.

A particular object of the invention is to provide an artificial light source which emits light closely approximating daylight. Another object of the invention is to provide a light source of high luminous efficiency. A further object of my invention is to provide a light source having a long useful life. Another object of my invention is to provide means whereby incandescent lamps can be used as ballast for an electric gaseous discharge device. Still another object of my invention is to provide means whereby failure of one of the ballast lamps will not render the gaseous discharge device inoperative. Still other objects and advantages of my invention will appear from the following detailed specification or from an inspection of the accompanying drawings.

20 The invention consists in the new and novel method of operation, and in the novel combination of elements, as hereinafter set forth and claimed.

In operating arc discharges from a constant potential source the use of a ballast in series with the arc is essential, due to the well known negative volt-ampere characteristic of this type of discharge. The resistance which has ordinarily been employed to provide this ballasting action has resulted in a considerable loss of energy which might be utilized in the production of light by the use of incandescent lamps as ballast, such as has been heretofore proposed. Unfortunately, however, this substitution has proved impossible, especially where a vapor arc is being operated. It is characteristic, for example, of the mercury vapor arc that at the instant of starting it draws over twice the normal current. Moreover, in alternating current devices of the rectifying or

40 "Cooper Hewitt" type there is a possibility during the starting period of transient arcing between the anodes, due to the condensation of mercury vapor on these anodes. In either case the incandescent lamps, if connected as ballast during this period, are subjected to an extreme overload which results in their rapid destruction. Moreover the incandescent lamps allow a high current surge at the moment the arc is started. This is due to the fact that the cold resistance of 50 the tungsten filament lamps commonly used is so low (being but a twelfth of the normal operating resistance thereof) that the initial current surge in the mercury arc is unduly accentuated. This combination of incandescent lamps with a 55 mercury vapor arc is extremely desirable, how-

ever, since the combined light of these units has been found to closely approximate daylight. I have now discovered a novel combination of elements cooperating in a novel manner, as described hereinafter, which permits the use of incandescent lamps as ballast for gaseous discharge devices despite these initial variations in arc current, without in any way impairing the life of the incandescent lamps. According to my novel invention the arc discharge is initiated with the usual ballast resistance in series with the discharge, and the incandescent lamps are pre-heated by operation on normal voltage during the starting period. Then after the arc current has decreased to substantially the normal value the incandescent lamps are substituted for the resistance. Due to the preheating of these lamps this transition is relatively smooth. The operation of the incandescent lamps at normal voltage during this starting period is also desirable because of the fact that the desired light quality is thereby attained from the moment the combined unit is switched on. As a further novel feature I provide means whereby this substitution of the incandescent lamps for the ballast resistance is avoided if the incandescent lamps are impaired, thus avoiding unnecessary shut downs of the gaseous discharge device. I have also discovered a novel means by which the delay period can be easily determined by the arc current itself, thus providing means whereby the starting period may be made the absolute minimum which is consistent with proper operation of the incandescent lamps.

25 For the purpose of illustrating my invention I have shown several embodiments thereof in the accompanying drawings, in which

30 Fig. 1 is a schematic diagram of the connections of an alternating current mercury arc lamp operating with incandescent lamp ballast,

35 Fig. 2 is a schematic diagram of a modification of the circuit of Fig. 1,

40 Fig. 3 is a schematic diagram of another modification of the circuit of Fig. 1, and

45 Fig. 4 is an elevational view of the relay used in the circuit of Fig. 3.

In these drawings, with special reference to Fig. 1 there is shown a mercury vapor arc lamp 1 of the "Cooper Hewitt" type, having a mercury cathode 2, starting band 3 and anodes 4. Said cathode 2 is connected through an inductance 5 to an intermediate point on the autotransformer 6. One of the anodes 4 is connected directly to one end of said autotransformer, while the other anode 4 is connected to the other end of said

autotransformer 6 through a heater unit 7, a ballast resistance 8, the magnet coil 9, and incandescent lamps 10. A single pole, double throw, mercury switch 11 is mounted on a pivoted magnetic support 12 which is within the field of the inductance 5. The middle terminal of said switch is connected to a point between the ballast resistance 8 and the magnet coil 9, while the terminal at the end of said switch which is normally down is connected to a tap on said autotransformer which is 64 volts (where the lamps 10 are 32 volt lamps) away from the end of said autotransformer to which said lamps are connected. The remaining terminal of said switch is connected directly to the same anode 4 with which the ballast is in series. As disclosed in Patent 1,990,152, granted Feb. 5, 1935 to Wilford J. Winninghoff, where the ballast is all inserted in a single anode lead the voltage applied between the anodes and the cathode should be asymmetrical in order to balance the arc current during successive half cycles. In the present case, with a standard mercury arc lamp having an arc tube an inch in diameter and fifty inches long, excellent results are obtained by connecting the inductance 5 to a tap which is 90 volts away from the lead to the direct connected anode and 194 volts away from the other end of said autotransformer. The support 12 is normally locked against pivotal movement both by the bell crank 13, and by a dog 14. Said dog 14 is adapted to be moved out of the locking position by the magnet coil 9, while the bell crank 13 is moved out of the locking position, after a predetermined delay, by means of a bimetallic element 15 which is in thermal relation to the heating unit 7. Where additional incandescent lamps are desired, in order to increase the red component of the light, lamps 16 are provided, these lamps preferably being of a low voltage type, say 32 volts, and connected to suitable taps on the autotransformer 6, in order to gain the greater luminous efficiency of these low voltage lamps. A mercury switch 17, of the type commonly called a shifter, is located in operable relation to the inductance 5 and has one terminal thereof connected to a point between said inductance and the cathode 2. The other terminal of said shifter is connected to the starting band 3 and also through a resistance 18 to an anode 4.

50 In the use and operation of this novel apparatus, upon application of a suitable potential to the autotransformer 6 current immediately flows through the lamps 16, and also from one end of said autotransformer through the lamps 10, magnet coil 9 and switch 11 back to a tap on said autotransformer. At the same time current flows from the same tap through said switch 11, ballast resistance 8, heating unit 7, resistance 18, shifter 17, and inductance 5 back to said autotransformer. This current energizes the inductance 5 which thereupon causes said shifter to open the circuit, interrupting the current flow through said inductance, with the result that a voltage surge is generated within said inductance 65 which initiates the arc through the lamp 1 in a well known manner. On one half cycle this arc current flows directly from one end of the autotransformer 6 to an anode 4, while on the other half cycle the current flows to the other anode 4 from the previously mentioned tap on said autotransformer through the switch 11, ballast resistance 8, and heating unit 7. These half-wave currents then combine in a full wave arc to the cathode 2, returning to the autotransformer through the inductance 5. Said inductance tends

to move the support 12 as soon as it is energized, but said support is locked against movement by the bell crank 13 until the discharge current has been flowing through the heating unit 7 for an interval of say 45 seconds. During this interval 5 the bimetallic element 15 gradually warps, forcing the bell crank out of the locking position, and at the same time the lamp 1 heats up and the current therethrough approaches normal. During this starting period the lamps 10 are, of course, operated continuously at normal voltage, while the lamp 1 is operated with a potential of 90 volts on the unballasted half cycle and 130 volts on the ballasted half cycle. Since the dog 14 is continuously held out of the locking position by the magnet coil 9 so long as current flows through the lamps 10, the support 12 is released as soon as the bell crank 13 is moved out of the locking position. Said support is thereupon immediately moved by the inductance 5 to change 20 the circuits through the switch 11. As shown, said switch 11 is preferably curved in order to disconnect one end terminal thereof before the other end terminal is connected. This is desirable although not essential, it being obvious that 25 with this construction both the lamps 10 and the ballast resistance 8 will be connected in series with the arc during the transitional stage, where- as if all three terminals of the switch are connected together during the transition all of the 30 ballast will be momentarily short circuited. In any case as the switch 11 again comes to rest a new circuit is established from the end of the autotransformer 6 through the preheated lamps 10, magnet coil 9 and switch 11 directly to an 35 anode 4, it being obvious that the ballast resistance 8 and heater unit 7 are now short circuited by the switch 11. Thus the lamp 1 continues to operate with the incandescent lamps as ballast, with a potential of 194 volts applied during the 40 ballasted half cycle. Said lamps 10 have a greater resistance than the ballast resistance 8, however, and hence the lamp 1 continues to operate with substantially the same current on each half cycle.

45 In case one of the lamps 10 burns out, or is otherwise destroyed, the arc in the lamp 1 will be extinguished, whereupon the switch 11 will be moved back to its starting position. The mercury arc will then be reinitiated as before, and 50 the bell crank 13 will be gradually moved out of the locking position. The magnet coil 9 will be deenergized, however, in this case so that the dog 14 will remain in the locking position until the faulty lamp 10 is replaced. In the meantime the 55 arc will continue to operate with the ballast resistance 8 connected in series therewith, only the incandescent lamps 10 being inoperative.

With the circuit of Fig. 1 failure of either of the ballast lamps 10 causes both to be rendered in- 60 operative. Where this is undesirable, as in locations that are not frequently serviced, the ballast may be divided and half placed in each anode lead in the conventional manner, as shown in Fig. 2. In this case the cathode 2 is connected 65 through the inductance 5 to the midpoint of the autotransformer 6, while each of the anodes 4 is connected in a symmetrical manner through a ballast resistance 8, heater unit 7, magnet coil 9, and a lamp 10 to an end of said auto- 70 transformer. Two mercury switches 11 are provided, each being mounted on a separated pivoted support 12. The midpoint of each switch is connected to a point between a magnetic coil 9 and a heater unit 7, while the terminal at 75

the end of each switch which is normally down is connected to a tap 32 volts away from the end of the autotransformer. The other terminal of each switch is directly connected to the 5 associated anode 4. Each support 12 is independently locked against movement by the inductance 5 in the same manner as in Fig. 1. The shifter 17 is likewise connected in the same manner as in Fig. 1, as are also the lamps 16. 10 The operation of the apparatus shown in this figure is quite similar to that previously described. Upon application of potential to the autotransformer 6 the lamps 10 and 16 are immediately lighted, and the arc is initiated in the usual manner in the mercury arc lamp 1. At the start the arc is operated with the two resistances 8 as ballast, while the lamps 10 are operated on their normal potential. After an interval the supports 12 are released, as previously described, whereupon 15 the lamps 10 are included in the respective anode circuits as ballast, and the resistances 8 are short circuited. In case either lamp 10 burns out the arc is extinguished. The switches 11 thereupon return immediately to their starting position and 20 the arc is reinitiated in the usual manner. After the desired interval the good lamp 10 is inserted in its anode lead as ballast in the previously described manner. The other support 12 continues to be locked by the dog 14 in its normal starting 25 position, however, due to the fact that the circuit through the associated magnet coil 9 is interrupted by the break in the lamp 10. Hence the ballast resistance 8 is left in this anode lead until the defective lamp 10 is replaced, and the arc operates 30 with resistance ballast on one half cycle and lamp ballast on the other half cycle. Thus failure of any incandescent lamp does not affect in the slightest either the continued operation of the mercury arc or of any of the other incandescent 35 lamps.

The circuit shown in Fig. 3 is similar to that of Fig. 1, except for the operating mechanism of the switch 11. In order to make the operation of this switch directly responsive to the current flowing in the mercury arc the relay mechanism shown in detail in Fig. 4 is incorporated in this circuit. As shown in these figures the armature 19 is pivotally supported by a yoke 20 in the outer fringe of the field of the inductance 5. The switch 11 is mounted on a heavy pivoted support 21 which is likewise carried by the yoke 20. A series of leaf springs 22 are affixed to the lower side of the armature 19, the longest thereof bearing against one end of a metal strip 23 which is attached at an intermediate point thereof to the support 21. The other end of said strip 23 turns downwardly and is adapted to engage the turned up end of the armature 19 when said armature is abruptly moved, locking the support 21 against rotation under the influence of the force exerted by the leaf springs 22. The armature 24 is pivotally supported by the yoke 20 adjacent to the coil 9 which is likewise supported by said yoke. The lower end of said armature is in the form of a hook which is normally so positioned as to engage a suitable notch in the support 21 to prevent operation thereof by the springs 22.

In the use and operation of this apparatus, upon application of a suitable alternating current potential to the autotransformer 6 current immediately flows through the lamps 10, lamps 16 and magnet coil 9, and likewise through the circuit comprised by the resistance 18, shifter 75 17 and inductance 5, energizing said inductance.

The shifter 17 is thereupon rotated to the open circuit position, and the ensuing voltage surge generated within said inductance initiates the arc in the lamp 1 in a well known manner. This current through said inductance is limited to a rather low value, of say 0.75 ampere, by the resistance 18, and hence the armature 19, being located in the fringe of the magnetic field about said inductance, is not appreciably attracted by the shifter current. As soon as the arc is initiated, however, a current 10 of the order of 6 amperes flows through said inductance. This large current saturates the core of said inductance and thus increases the stray field about the armature 19, causing it to be suddenly attracted toward said inductance. As a 15 result of this sudden movement of the armature the bent up end thereof engages the turned down end of the strip 23, locking the support 21 against movement before the springs 22 can overcome the inertia of the support 21 to move it. The 20 armature 24 is, of course, held out of the locking position due to the lamp current flowing through the magnet coil 9. As the arc current decreases the field about the inductance 5 gradually decreases, lessening its attraction for the armature 25 19, with the result that the springs 22 cause said armature to gradually recede from said inductance until eventually, after the arc current has dropped to substantially the normal operating value, said armature releases the metal strip 23. 30 This unlocks the support 21, and allows the springs 22 to force said strip 23 upwardly, moving the support 21 and switch 11 to the normal operating position. The lamps 10 are thereupon included in the arc circuit, and the ballast resistance 8 short 35 circuited in the same manner as in the circuit of Fig. 1. In order to obtain this action of the armature 19 it is essential, of course, that said armature should remain balanced and not make contact with the iron core of the inductance 5, and 40 means such as a fiber spacer is commonly used to prevent such contact, which would freeze the armature and prevent its response to the decreasing current.

If a lamp 10 burns out the arc is extinguished, 45 and then reinitiated in the manner previously described. The armature 24 remains in the locking position, however, and thus prevents the operation of the switch 11, with the result that the arc continues to operate with the resistance 8 50 as ballast until the lamp 10 is replaced.

While I have illustrated my invention by reference to specific embodiments thereof it is to be understood that it is not limited thereto, but that various changes, substitutions or omissions within the scope of the appended claims may be made either in the structure or the mode of operation, without departing from the spirit thereof. It is, moreover, to be understood that the invention is applicable to the various types of gaseous discharge devices, operating with either a hot or cold cathode, or with two cathodes and a reversing discharge, whenever the initial operating characteristics of the discharge device preclude the immediate insertion of an incandescent lamp 60 in series therewith.

I claim as my invention:—

1. In combination, an electric gaseous discharge device, a ballast resistance connected in series therewith, an incandescent lamp, means to substitute said lamp for said resistance, and means to preheat the filament of said incandescent lamp before it is connected in series with said device. 70

2. In combination, an electric gaseous discharge device, a ballast resistance connected in series 75

therewith, an incandescent lamp, means responsive to current flow through said discharge device to substitute said lamp for said resistance, means to prevent the immediate response of said last mentioned means, and means to preheat the filament of said incandescent lamp before it is connected in series with said device.

3. In combination, an electric gaseous discharge device, a ballast resistance connected in series therewith, an incandescent lamp, means to substitute said lamp for said resistance, and means to render said last mentioned means inoperative whenever the filament of said lamp is destroyed.

4. In combination, an electric gaseous discharge device, a ballast resistance connected in series therewith, an incandescent lamp, means responsive to current flow through said discharge device to substitute said lamp for said resistance, means to prevent immediate response of said last mentioned means, means to preheat said incandescent lamp, and means operative upon failure of said incandescent lamp to prevent substitution of said lamp for said resistance.

5. In combination, an electric gaseous discharge device having a cathode and two anodes, an autotransformer, one of said anodes being connected to a point on said autotransformer through a ballast resistance, the other of said anodes being connected to another point on said autotransformer, a connection from said cathode to an intermediate point on said autotransformer, an incandescent lamp connected on one side to the end of said resistance which is connected to said autotransformer and on the other side to a point of higher potential on said autotransformer, means to open the connection between said resistance and said autotransformer, and means to short circuit said resistance.

6. In combination, an electric gaseous discharge device having a cathode and two anodes, an autotransformer, one of said anodes being connected to a point on said autotransformer through a ballast resistance, the other of said anodes being connected to another point on said autotransformer, a connection from said cathode to an intermediate point on said autotransformer, an incandescent lamp connected on one side to the end of said resistance which is connected to said autotransformer and on the other side to a point of higher potential on said autotransformer, means responsive to current flow through said discharge device to open the connection between said resistance and said autotransformer and to short circuit said resistance, and means to prevent the immediate response of said last mentioned means.

7. In combination, an electric gaseous dis-

charge device, a ballast resistance and an inductance connected in series therewith, an incandescent lamp, means responsive to current flow through said discharge device to substitute said lamp for said resistance, and means comprising a locking mechanism responsive to the field about said inductance to prevent operation of said last mentioned means until the current through said discharge device has decreased to a predetermined value.

8. In combination, an electric gaseous discharge device, a ballast resistance and an inductance connected in series therewith, an incandescent lamp, switching means to substitute said lamp for said resistance, an armature in the field of said inductance, a yielding connection between said armature and said switching means, and means on said armature to lock said switching means against movement, the inertia of said switching means being sufficient to prevent operation thereof by said yielding connection before said armature locks said switching means whenever a current of more than a predetermined value suddenly flows through said inductance, said yielding means then balancing said armature against the attraction of said inductance, the resilience of said yielding means being sufficient to move said armature to unlock said switching means when the current through said inductance falls to a predetermined value.

9. In combination, an inductance, an armature in the field of said inductance, a switching means, a yielding connection between said armature and said switching means, and means on said armature to lock said switching means against movement, the inertia of said switching means being sufficient to prevent operation thereof by said yielding connection before said armature locks said switching means whenever a current of more than a predetermined value suddenly flows through said inductance, the resilience of said yielding means being sufficient to move said armature to unlock said switching means when said current falls to a predetermined value.

10. The method of operating a gaseous discharge device which comprises starting the discharge in said device while utilizing a resistance as ballast, preheating the filament of an incandescent lamp by passing therethrough a current equal to the current flowing through said discharge device under conditions of thermal equilibrium, and then substituting said lamp for said resistance after the discharge current has reached a stable value.

LEROUY J. BUTTOLPH.
